AUTOMATIC CONTROL OF HOT-BLAST TEMPERATURES

Truman H. Kennedy, McKeesport, and Emmons T. Mortson, Pittsburgh, Pa., assignors to National Tube Company, a corporation of New Jersey

Application October 21, 1944, Serial No. 559,856

2 Claims. (Cl. 236—44)

1

This invention relates to the control of hot blast temperatures whereby a metallurgical blast furnace is maintained at its optimum operating condition.

Among the objects of the invention is the provision of apparatus for automatically varying the temperature of the hot blast supplied to the furnace in accordance with the absolute humidity of the unheated indrawn blast air, whereby compensation for variations in absolute humidity of such air are effected by raising or lowering the temperature of the blast.

Another object is the provision of a method of regulating the temperature of the hot blast whereby the furnace operates at its optimum condition regardless of changes in the humidity of the atmosphere.

These and other objects of the invention will further appear in the following description.

It is desirable, in the interests of uniform blast furnace operation, and consequently uniformity of product, to operate the furnace as nearly as possible under constant conditions, that is, with a uniform weight, distribution, and composition of burden, and with a uniform air blast pressure and temperature. Attainment of the last named condition has been difficult, if not impossible, because variations in the amount of moisture in the air drawn into and heated by the blast furnace stoves results in varying markedly the effective heat content of the blast reaching the furnace, due to the fluctuating chilling effect of moisture in the indrawn air.

Our invention provides means whereby the temperatures of the blast delivered to the blast furnace is automatically varied to compensate for fluctuations in humidity of the atmosphere, whereby the effect of the blast upon the burden is made at least substantially constant regardless of such humidity variations. Our apparatus consists broadly of means which by itself would function to keep the temperature of the blast at a constant set point, plus means responsive to changes in the absolute humidity of the unheated indrawn air to vary such set point of the first means in accordance with a previously determined ratio.

degrees change from standard, blast temperature
grains moisture/ft.³ change from

standard, unheated indrawn air
which is found to maintain the heating effect of the air delivered to the blast furnace at least substantially constant.

The invention will be more clearly understood

2

by reference to the accompanying drawings, in which:

Figure 1 is a schematic view of the stove and its air supply and air delivery means;

5 Figures 2A and 2B connected and taken as a single figure forms a partly schematic view of the means for determining the humidity of the air entering the stove;

10 Figure 3 is a view of the control circuit employed for varying the position of the mixer valve in accordance with the humidity of the air as determined by the apparatus of Figure 2; and

15 Figures 4 and 5 are views in perspective of mechanical relay mechanisms employed in the circuit of Figure 3.

As shown in Figure 1, a stove 1 for heating the air delivered to a metallurgical blast furnace (not shown) is supplied by main 2 with air drawn by the blowing engines from the atmosphere, 20 said air being led into stove 1 through pipe 3 and, after being heated, being led out by pipe 4. The latter pipe feeds into main 5, which leads to the tuyères of a blast furnace, the heated air mixing with unheated, indrawn blast air from bleed line 6, and the amount of such unheated air mixed being determined by the position of mixer valve 7, which is controlled by shaft 8.

It is obvious that the temperature of the blast air in main 5 may be varied by varying the setting 30 of mixer valve 7. Opening of the valve 7 wider allows the entry of more cold air and thus reduces the temperature of the blast, whereas moving of the valve toward the closed position restricts the entry of cold air and thus raises the temperature of the blast. As stated above, the apparatus of the present invention comprises means which by itself would automatically position valve 7 to maintain the temperature of the blast air constant regardless of variations in the 40 humidity of the atmosphere, and means for varying the constant or set temperature, at which the first control means would maintain the air blast, in accordance with variations in the humidity of the indrawn, unheated air.

45 The first of the above control means, namely that which by itself would maintain the temperature of the air blast constant regardless of humidity changes, consists of a thermocouple 9 positioned in air blast main 5 to determine the 50 temperature of the heated air blast as it enters the furnace. Thermocouple 9 has leads 10 and 11 which are connected as shown to a control network N', shown in Figure 3. For the purpose of the present discussion, it will be assumed for the moment that there is no connection between

network N and network N', that is, the driving means generically shown as 128a is not connected to contact or set point 98' of network N'. Under such conditions, network N' would function to maintain the temperature of the air blast in main 5 at the temperature required by the then manually set point 98'. This will be apparent from the following discussion of the structure of network N' and its manner of operation.

The network N' comprises a slidewire 97', whose position with respect to its contact or set point 98' corresponds with the existing temperature of blast air in main 5, and a slidewire 99' whose position with respect to its contact 100' corresponds with the setting of valve 1.

Thermocouple 9 produces a voltage responsive to changes in temperature of the blast air in main 5. In the self-balancing potentiometer arrangement shown on the drawing, the voltage produced by thermocouple 9 is automatically balanced against the effective voltage of potentiometer slidewire 102'. Upon change in air blast temperature, the galvanometer 103' deflects to effect, through mechanical relay mechanism 104', adjustment of the potentiometer slidewire 102' with respect to its contact 105' in such sense and to such extent that the voltage of thermocouple 9 is again balanced. The disc 106', upon which the potentiometer slidewire 102' is mounted, is coupled, as by shaft 107', to the disc 108' upon which the slidewire 97' of network N' is mounted, so that each different position of contact of set point 98' with respect to slidewire 97' corresponds with a different temperature of the air blast. The resistance of slidewire 97' is preferably, though not necessarily, concentrated in its central section of limited angular extent, for example, 60 degrees.

The current for the potentiometer slidewire 102', derived from any suitable source, such as a battery 109', is, from time to time, adjusted, as by variation of rheostat 109a' to maintain it at standard value for which the slidewire 102' is calibrated. The usual standard cell and switching arrangement for effecting the standardization is not shown.

The mechanically relay mechanism 104', diagrammatically shown in Figure 4, may be of the type fully described and claimed in Squibb Patent No. 1,935,732. In brief, the pointer 110' of the galvanometer 103' is intermittently clamped against the stationary stop 111' by the clamping member 112' which is periodically rocked by a cam (not shown) on the shaft 113' continuously rotated at suitable speed, for example, thirty revolutions per minute. While the needle is so clamped, the feelers 114', 114' are released, by a cam (not shown) on shaft 113', for movement toward each other by their biasing spring 115'. If the pointer is clamped to right or left of its neutral or central position, the lower end of one or the other of the feelers 114', 114' during its movement, engages the pin 116' extending from the driving clutch member 117' and swings it about its pivot 118' in a sense and to extent corresponding with the sense and extent of deflection of the pointer 110' from its neutral position. While so displaced from its neutral position, the driving clutch member 117' is moved, under the control of a cam (not shown) on the shaft 113', into engagement with the driven clutch member 119' attached to aforesaid shaft 107'. Within the same revolution of shaft 113', one or the other of the cams 120 engages driving clutch member 117' and returns it to the neutral position shown

in Figure 5 of the drawing, and since, during this time, the clutch members 117' and 119' are in engagement with each other, each of the slide-wire discs 106' and 108' is moved in a direction and to an extent corresponding with the deflection of the galvanometer pointer.

For the purpose of explanation, it is assumed that when the temperature of the air blast is at a normal figure, the contact 98' is an engagement with the midpoint of slidewire 97' and that slidewire 108' is moved in clockwise direction as the temperature falls, and in counterclockwise direction as the temperature rises. For brevity, that relative position of slidewire 97' and contact 98' which corresponds with the desired temperature is termed "the normal control point".

The end coils or resistances 121', 122' connected between the terminals of the slidewire 97' and the terminals 123', 124' of network N', determine the limits between which the ratio of the impedances of the two upper arms of the bridge is varied by adjustment of slidewire 91' with respect to contact 98'. The terminals 123', 124' of network N' are connected to any suitable source of direct or alternating current. They may, for example, be connected to the secondary of a transformer (not shown) whose primary is energized from the alternating current line 125'.

The lower pair of arms of the network N' include the adjustable resistances 126' and 127' connected between terminals of the slidewire 99' and the aforesaid supply terminals 123', 124' of the network.

The reversible motor M', of any suitable type, is suitably connected through shafting and gearing, generically illustrated by broken line 8, to the mixing valve 1 and is controlled by a reversing switch comprising contacts 129', 130', and 131', operated in response to unbalance of the network N' by the relay R' of any suitable type, for example, a contact galvanometer. The motor M' is energized from any suitable source of current connected to the terminals 132', 132' of its control circuit. The motor M' is also mechanically coupled to the supporting disc 133' of the slide-wire 99' to effect, upon unbalance of network N', adjustment of slidewire 99' with respect to its contact 100' in that sense required to restore the network N' to balance.

It is characteristic of the control system thus far described that, upon change of air blast temperature, the network N' is unbalanced by movement of slidewire 97' to an extent corresponding with the extent of the temperature change and is rebalanced by adjustment of slide-wire 99' concurrently with actuation of the valve 1 by motor M'. Accordingly, for every air blast temperature there is a corresponding position or setting of valve 1.

When the relations between the extents of valve adjustment and the extents of adjustment of slidewires 97' and 99' are so selected that the system is stable, the temperature load characteristic of the system is a drooping one; that is, the control system tends to maintain the air blast temperature constant at a magnitude which becomes less and less with increase in volume of blast air to the furnace. Unless such relations producing a drooping characteristic are selected, the control system is unstable.

To maintain the air blast temperature substantially constant at the desired magnitude independent of fluctuations of the volume/min. of the air blast, the network N' is provided with another pair of arms comprising, or consisting

of the resistors 134', 135' of material such as nickel having a substantial temperature coefficient of resistance. The energization of heater coil 136', which is in intimate heat transfer relation with resistor 134', is controlled by contacts 137', 138' of relay R1' responsive to unbalance of a second or subsidiary bridge whose arms comprise resistances 134', 135', 121', resistance 122' and slidewire 97'. Energization of the heater 139', which is in intimate heat transfer relation with resistor 135', is controlled by the contacts 140', 138' of relay R1'.

Energization and reversal of the reversible motor MA', which is mechanically coupled, as generically indicated by broken line 141', to the resistances 126' and 127' of the main bridge of network N', is controlled by aforesaid contacts 137', 138', 140' of relay R1'.

The magnitudes of resistance of resistors 134', 135', are so chosen that when the slidewire 97' is in the position corresponding with the desired air blast temperature, the subsidiary bridge or network is in balance. Assuming, for example, the temperature of the air blast has fallen from the normal magnitude so as to reduce the impedance between terminal 123' and contact 98' of the network and concurrently to increase the impedance between the contact 98' and terminal 124' of the network, the relay R1' responds to the unbalance to energize the heater coil 139' gradually to increase the resistance of resistor 135' and so tend slowly to restore balance of the subsidiary network with contact 98' and slidewire 97' relatively displaced from the control point. Until such balance is restored, the contacts 138' and 140' of relay R1' remain closed to effect energization of motor MA' for adjustment of resistances 126' and 127' in that sense unbalancing or tending to unbalance the main network N' which causes, through relay R1', energization of motor M' in that sense effecting further closing of valve 1. This secondary control action, due to adjustment of resistors 126' and 127', is distinct from and in addition to the primary control action due to movement of slidewire 97' in response to change in air blast temperature.

When the resistance of 135', because of the heat received from coil 139', has attained that value which effects rebalance of the subsidiary network, the relay R1' breaks the circuit to the heating coil 139' and to the motor MA', whereupon resistance 135' begins to cool with consequent decrease of its resistance.

If the temperature of the air blast is rising toward normal magnitude thereof at the same rate that resistance 135' is cooling, the auxiliary network remains in balance and there is no further adjustment of the droop-correcting resistors 126' and 127' by motor MA'.

If the air blast temperature is rising toward normal magnitude thereof at a rate slower than the rate at which resistance 135' is cooling, the auxiliary network is again unbalanced in the same sense as before and relay R1' effects closure of contacts 138' and 140' again to energize the heater coil 139' and the motor MA' to effect further adjustment of the impedances 126' and 127'; however, because the slidewire 97' has moved toward the control point, coil 139' is energized for a shorter time than before to effect rebalance. The cyclic heating and cooling of resistor 135' continues with increasingly shorter periods of energization of heater 139' and motor MA' until the slidewire attains the control point.

If, on the contrary, the air blast temperature is increasing more rapidly than the rate at which resistor 135' is cooling, the auxiliary network is unbalanced in the opposite sense and relay R1' responds to effect energization of heater coil 136' slowly to increase the effective magnitude of resistance 134' and also, by closure of its contacts 137' and 138', to effect reverse adjustment of the resistances 126' and 127' by reverse operation of the motor MA'. When the effective magnitude of resistance 134' has, because of heat received from heater 136', attained that value sufficient to rebalance the subsidiary network, relay R1' responds to deenergize heater 136' and motor MA' whereupon resistance 134' begins to cool.

From the foregoing, it will be understood that when the air blast temperature increases above the desired magnitude, there is at once effected a primary adjustment corresponding with or proportional to the deviation of slidewire 97' from the control point and that there is subsequently, or more slowly, effected secondary adjustments of the valve 1 due to the cyclic balancing and unbalancing of the subsidiary network continuing until slidewire 97' returns to the control point.

Thus, the subsidiary network including the resistors 134', 135' and their associated heating coils 136', 139', prevents the main network N' from remaining permanently in balance so long as the slidewire disc 108' is away from the position corresponding with the desired air blast temperature; so long as any deviation from said desired temperature exists, the subsidiary network is cyclically unbalanced to effect adjustment of the impedances 126' and 127' of the main network, in that sense providing for return of the air blast temperature to the desired magnitude and at a rate which progressively decreases as the desired temperature is approached, thus to avoid overshooting or hunting.

The rheostats 142', 143' in series with the heater coils 139' and 136' may be provided to provide for adjustment of the rate at which droop-corrective action is effected. Increase in magnitude of the series resistances 142', 143' requires the contacts of relay R1' to be closed for a longer time to procure a given increase in temperature of the resistors 134' and 135' and consequently motor M' runs for a longer interval before a balance of the subsidiary network is effected. Rheostats 142', 143' may be mounted on the same shaft or on separate shafts, depending upon whether symmetrical or unsymmetrical response is desired.

From the foregoing it is manifest that network N', acting with thermocouple 9 and mixer valve 1, will maintain the temperature of the blast air at the temperature required by the position of contact point 98'. In accordance with the present invention, however, contact point 98' is not manually set, as was assumed above for ease of understanding that portion of the apparatus, but is in turn operated or set automatically by means responsive to the humidity of the unheated, indrawn blast air in such manner that the temperature of the air blast in main 5 is varied to compensate for variations in humidity, in order that the air blast may have a substantially constant heating effect upon the burden of the blast furnace.

The means for thus automatically setting contact 98' is shown in Figures 2A, 2B, and the upper part of Figure 3. As shown in Figure

1, unheated blast air in main 2 is drawn off through pipe 12 in order to obtain a sample of such indrawn air. Such sample passes through throttle valve 13 and reducing valve 14, and then through pipe 12 (Figure 2A) into a means for constantly measuring the humidity of such sample.

Air passing through pipe 12 is led through air coils 18, said coils being immersed in constant temperature water in tank 16. Constant temperature water is obtained from tank 17, which is fed by tap water through pipe 19 and valve 20, allowed to flow into tank 17, in which are located steam coils 18, and thence through pipes 21 to tank 16, from which it flows to the sewer through pipes 22. Exhaust steam from coils 18 likewise flows to the sewer through pipe 24. Steam to coils 18 is fed through supply pipe 23 in amounts governed by the thermometer 26 located in tank 16. Said thermometer, which may be of the fluid expansion type is connected by conduit 27 to the control device shown in Figure 2B, to regulate valve 24 located between the steam supply 25 and pipe 23 in such manner that the water in tank 16 and consequently the air in coils 18 is brought to a predetermined constant temperature. The tanks 16 and 17 and pipes 21 and 23, as well as the receptacle 88 housing the wet bulb thermocouple, subsequently to be described, and the conduit 85 delivering constant temperature air to receptacle 88 from coils 18, are all carefully insulated to prevent radiation and conduction of heat therefrom, and to maintain the temperature of the air sample uniform and constant.

Control of valve 24 by thermometer 26 is effected by means of the control means shown in Figure 2B. The device shown for purposes of illustration is that disclosed in the patent to Harrison et al., No. 2,125,109, July 26, 1938, although it is obvious that other known control means may be substituted therefor. The control mechanism shown, as above explained, is for the purpose of adjusting valve 24 in response to thermometer 26 to maintain a constant water temperature within tank 16.

The fluid pressure in chamber 26, which increases and decreases as the water temperature within tank 16 rises and falls, respectively, is transmitted by conduit 27 to a pressure responsive element 28, shown as a Bourdon tube of helical form having its stationary end connected to the conduit 27, and having its movable end secured to an arm 29 which is pivoted to turn about an axis 30, clockwise or counterclockwise, as the pressure in the tube rises or falls, respectively.

Through suitable connections, the oscillations of the arm 29 give motion to the valve 31, which as shown, forms part of a control pressure regulator or air controller unit 32, and regulates the escape of air from, and thereby regulates the control air pressure in the regulator chamber 33. The latter receives air through a pipe 34, a coupling 35 and pipe 36 from air supply means, which as shown, comprises a chamber 37 receiving air under pressure through a supply pipe 38, and comprises means for maintaining a substantially constant pressure in the chamber, somewhat smaller than the pressure in the pipe 38, notwithstanding fluctuations in the last mentioned pressure. The flow through the pipe 34 into the pipe 36 is restricted as by means of restricted port 39, in the coupling 35 between the pipes, so that the pressure in the pipe 36 may

normally be the same as that in the chamber 33, and below that in the chamber 37.

The variable air pressure maintained in the chamber 33 is transmitted through a pipe 40 in free communication through the coupling 35, with the pipe 38 to the pressure regulator diaphragm chamber 41 of a fluid pressure relay device having a main pressure chamber 42. The latter receives air under pressure through the passage 43 from a suitable source shown as the chamber 37, and means are provided for maintaining a pressure in the chamber 42 which varies with the pressure in the diaphragm chamber 41 and hence with the control pressure in the regulator chamber 33. The means shown for the purpose comprises a valve member 44 actuated by the flexible diaphragm 45 between chambers 42 and 41, which throttles the air through inlet 43 more or less, and the outlet of air from chamber 42 through a vent 46, less or more as the pressure in the chamber 42 rises above or falls below the pressure in the chamber 41. The pressure in the chamber 42 is transmitted by a conduit 47 to the pressure chamber 48 of the valve 24, which is a fluid pressure valve adapted to admit either a heating or cooling fluid to the coils 18 through a supply pipe 23 as the control pressure in the regulator 32 rises and falls.

In the controller illustrated, movements of the arm 28 give movements to the valve 31 through a link 48, a rocking element 49, a floating lever 50, a link 51 connecting parts 49 and 50, and a bell crank lever 52 connected by pivot 53 to the lever 50, and carrying a pin 54 engaging the valve 31. The value of the control quantity which the apparatus tends to maintain may be manually adjusted, as conditions make desirable, by a rocking element 55 connected to the lever 50 by a link 57. The latter, in effect, forms an adjustable fulcrum for the lever 50, and mechanism hereinafter described adjusts the lever 52 relative to the lever 50 to modify the action of the latter on the valve 31, in response to variations in pressure conditions within the device 32, resulting from changes in the position of the valve 31.

The rocking element 49 is mounted to oscillate about the axis of a shaft 58, and carries a pointer 59 which may indicate the value of the control quantity on a suitable scale in the instrument (not shown), and carries a pen point or stylus at its free end which is adapted to make a record on a chart disc (not shown). The chart is rotated by a constantly rotating chart shaft (not shown) and is provided with scale lines. As shown, the rocking element 49 includes an arm 60 to which the corresponding end of the link 29 is connected, and a second arm 61 to which the corresponding end of the link 51 is connected.

The rocking element 55 is mounted to oscillate about the axis of the shaft 58 and includes an index arm 62 which indicates on the same scale with which the pointer 59 cooperates the normal value of the control quantity. When the control quantity is at its normal value, the pointer 59 will be directly in front of, and will register on the scale with the index 62. As shown on the drawing, the position of the pointer 59 corresponds to an actual value of the control quantity greater than the normal value. The element 55 includes an arm 63 to which the corresponding end of the link 57 is connected. In the valve operating means shown, the floating lever 50 is suspended from the arms 61 and 63 by members 64 and 65 which engage the lever 52 at spaced

apart points and constitute substantially vertical suspension links through which the lever is suspended. In consequence, gravitational forces are utilized in eliminating lost motion in effecting an adjustment of the lever 50, through either of said links by angular adjustment of the corresponding elements 49 and 55. As previously explained, the element 49 is given angular adjustments in accordance with changes in the value of the control quantity acting through the parts 28, 29, and 48. The rocking element 55 may be manually adjusted about the axis of the shaft 58 to increase or decrease the normal value indicated by the index 62, and to simultaneously and correspondingly raise or lower the fulcrum for the lever 50 formed by the lower end of the link 57 by an adjusting element 64 having an arm 65 connected by a link 66 to the element 55. As shown, the adjusting element 64 is in the form of a rotatable element which may be normally held stationary by frictional means, and is provided with a slot 67 for engagement by a screw driver by which the element 64 may be angularly adjusted to thereby angularly adjust the element 55, when adjustment in the normal value of the control quantity is desirable.

The device 32 as shown, comprises a cup-shaped casing element detachably connected at its open end to a head 68. The former is formed with an aperture through which the air supply pipe 36 communicates with the space 33, and the latter, with an aperture in which is mounted the bleeder or vent nozzle 69 through which air escapes to the atmosphere from the chamber 33 at a rate depending on the adjustment of the valve member 31. Preferably and as shown, the nozzle member 69 has an external globular end surface surrounding the outer end of the nozzle passage, and the valve member 31 is a piece of sheet metal extending transverse to the length of, and movable toward and away from the outer end of the nozzle passage. As shown, the valve 31 is pivoted to turn about a shaft 70 which may be mounted on the head 68. A spring (not shown), coiled about shaft 70, gives the valve 31 a slight bias toward its closed position, in which it engages the nozzle member 69 at the margin of the nozzle passage.

A resilient bellows element 71 located within, but not filling the casing of the device 32, has one end secured to the end head 68, and has its other end closed so that an increase or decrease in the pressure within the space 33 between the casing of the device 32 and the bellows 71, tends to contract and expand the latter. Within the bellows 71 and separated from the latter by an inter-bellows space 72, is a smaller bellows element 73 which has one end secured to the end head 68 at the margin of an opening 74 in the latter, through which the interior of the bellows 73 is in free communication with the atmosphere at all times. The inter-bellows space 72 communicates with the atmosphere through a restricted passage 75 formed in the end head 68. Advantageously, an adjustable obturator 76 is provided to regulate the flow capacity of the passage 75.

The movements of the free end 71 of the bellows 73 modify the operating effect of the lever 50 on the valve 31 through parts shown, which comprise a link 78 connecting the bellows head 70 to a lever 79 mounted to oscillate about the shaft 70 and pivotally connected by a pivot shaft 80 to a lever 81. The latter is connected by a pivot shaft 82 to the lever 52, and has an adjustable fulcrum formed by a pivot pin 83 carried

by the lever 81 and slidably received in a diametral slot 84 formed in an angularly adjusted disc (not shown).

The link 78 which is axially disposed in the bellows 73, and may be rigidly secured to the end head 71 of the latter, is preferably connected to the lever 79 for adjustment relative to the latter, in such manner as to vary the effective length of the link.

Clockwise movement of the lever 52 about its pivot 82 gives an opening movement to the flapper valve 31 through the action on the latter of the pin 54 carried by the lever 52. The pin 54 is advantageously connected to the lever 52 for movement toward and away from the pivot 82 to thereby vary the extent of valve movement produced by a given angular movement of the lever 52.

Each of the bellows elements 71 and 73 has longitudinal resilience and, consequently, a definite length when the pressures acting on its inner and outer walls are the same. When the external pressure on either bellows is less than, or exceeds the pressure within the bellows, the bellows will elongate or contract as required to make the differential of the effects of those pressures on the bellows equal to the opposing resilient bellows force resulting from the elongation or contraction of the bellows, that force, of itself, always tending to return the bellows to its normal or unstressed length. On an increase in the pressure within the Bourdon tube 28 and consequent movement of the link 51 upward, the lever 52 acts on the valve 31 to move the latter away from the nozzle 69 and thereby reduce the pressure in chamber 33. The pressure reduction in chamber 33 elongates the bellows 71 and thereby enlarges the inter-bellows space 72 and reduces the pressure in the latter, owing to the relatively slow inflow of air permitted by the restricted passage 75. The reduction of the pressure in the space 72 elongates the bellows 73 and thereby moves the link 78 to the right. The movement thus given the lever 79 moves the parts 81, 52 and 50 to the right and thereby permits of a return movement of the valve 31 toward the nozzle 69, partially neutralizing the effect of its initial movement away from the nozzle 69.

The extent of such return movement of the valve 31 produced by a given movement of the link 78, depends upon the relation of the movement of the pivotal connection 82 to the movement of the pivotal connection 80, and that relation is dependent upon the inclination of the slot 84. With the slot 84 inclined generally as shown, a counterclockwise turning movement of the lever 79 about the shaft 70 will produce a clockwise movement of the lever 81 about the pivotal connection 80 accordingly, as the direction of the length of the slot 84 diverges counterclockwise, respectively, from the direction of the plane including the axes of the shaft 80 and 83. With the adjustment of the slot 84 such that the counterclockwise movement of the lever 79 causes the lever 81 to turn clockwise about the shaft 80, the angular movement of the pivot 82 about the shaft 70 will be less than the angular movement about the latter of the lever 79.

The enlargement of the inter-bellows space or chamber 72 reduces the pressure therein and thereby creates an inflow of air into 72 through the passage 75, which tends to restore the pressure in the chamber 72 to its normal equality with the pressure of the atmosphere. As the pressure in the chamber 72 builds up, the bellows

13 shortens and thereby again moves the valve 31 away from the nozzle 69 and back toward the position into which it has moved on the original change in position of the link 51, provided the latter has not been moved in the direction of its length in the meantime as a result of a change in the Bourdon tube pressure. The converse of the actions just described occur on a decrease in the pressure in the Bourdon tube 28, and a corresponding adjustment of the link 51 downward.

15 In the normal use of this recording controlling apparatus as hereinbefore described, the proportions and adjustments of the parts are such that upon an increase or decrease of air temperature in air coils 15 of usual magnitude requiring some increase or decrease in temperature of water through tank 16 to maintain the desired air temperature, the initial resultant decrease or increase in the water temperature will tend to produce a movement to its limit, of the valve controlling the media supply, in the direction to return the control temperature to its normal value, which will therefore be of such magnitude that the new media supply will be of higher or lower temperature, respectively, than that required to maintain the normal control temperature with the new temperature of incoming air. Such a control operation of itself, is essentially unstable, and must result in hunting. The control action described is modified, and the hunting tendency eliminated or minimized by the initial movement of the link 18, which effects what is commonly called a follow-up adjustment. The latter can be made sufficient to insure a control which is stable and not hunting. In such case, however, the follow-up adjustment, if not later neutralized, will result in the maintenance of a tube air temperature necessarily, and significantly lower with a vast incoming air to tube air temperature differential than with a lesser differential.

20 The control adjustment resulting from the second or return movement of the link 18, occurring as the pressure in the inter-bellows space 12 approaches its normal atmospheric value, following a departure from that value, is a compensating adjustment which may be made to neutralize the effect of the follow-up adjustment slowly enough to substantially eliminate the effect of the follow-up adjustment on the control temperature when the tube air to incoming air temperature differential is steady, without giving rise to an objectionable hunting tendency.

25 Returning to Figure 2A, constant temperature air, which is a sample of the air in main 2, after contacting the aforementioned expansion fluid thermometer 26 passes into contact with a wet bulb thermometer, or any other suitable device responsive to changes in humidity, whereby 30 temperature of air is evidenced as function of its humidity. In the apparatus shown there is employed, for such purpose a wet bulb thermocouple 88, which is located in receptacle 86, and which is constantly saturated by water through wick 94, contained in receptacle 91, which is supplied with water from inlet 92. Overflow water in receptacle 91 flows out through pipe 93. After flowing past wet bulb thermocouple 88 and dry bulb thermometer 87, which affords a constant check on the maintenance of uniform temperature of the air sample, the air is exhausted to atmosphere through opening 89 and 90, respectively.

35 It is now evident that the constant temperature air through air coils 15, which is a true

sample from the cold blast main 12, will always present itself to the wet bulb thermocouple, or any other known humidity responsive element, at a constant temperature. Thus, any change in humidity of the air will evidence itself by changing the rate of evaporation at the wet bulb, or the like, with a consequent variance in the humidity dependent temperature thereon. Thus, a differential of varying degree having one and only one variable has been established; that variable being the changes in humidity of air through air coils 15. From this it can be seen that this differential can be utilized for controlling the aforementioned hot blast mixer valve for changes in humidity of incoming blast air to furnace.

40 As shown in Figure 3, leads 85 and 86 from wet bulb thermocouple 88 are led into network N, which is similar in all respects to network N'. Corresponding elements in the two networks are similarly lettered and numbered, with the exception that in network N' the reference characters are primed. As will be apparent from the previous description of network N', the voltage produced by thermocouple 88, which is responsive to the humidity of the indrawn, unheated blast air, is automatically balanced against the effective voltage of potentiometer slidewire 102. Upon change of humidity of such air, galvanometer 103 deflects to effect, through mechanical relay mechanism 104, adjustment of the potentiometer slidewire 102 with respect to its contact 105 in such sense and to such extent that the voltage of thermocouple 88 is again balanced. The disc 106, upon which the potentiometer slidewire 102 is mounted, is coupled by shaft 107 to the disc 108, upon which the slidewire 97 is mounted, so that each different position of contact of point 88 with respect to slidewire 97 corresponds with a different humidity of the unheated, indrawn blast air.

45 Reversible motor M, operated by relay R, will thus function to turn disc 103, carrying slidewire 99, to effect upon a balance of network N adjustment of slidewire 89 with respect to its contact 100 in that sense required to restore the network N to balance. Thus, upon change of humidity of the unheated, indrawn blast air, network N is unbalanced by movement of slidewire 97 to an extent corresponding with the extent of the humidity change, and is rebalanced by adjustment of slidewire 89 concurrently with actuation of the control or set point 88' of network N' by motor M, acting through the driving means generically shown as 128a. Accordingly, for every value of humidity of the unheated, indrawn blast air, there is a corresponding position or setting of control or set point 88' of network N'.

50 55 60 65 70 75 Driving means 128a may, if the positions of the parts allow it, be a shaft from motor M leading directly to a gear box driving an adjusting screw upon which is a travelling nut connected to control or set point 88'. It is usually more convenient, however, particularly when networks N and N' are in different cabinets, to employ an electrical means to connect the shaft of motor M to the control point 88', such electrical means being of a type which retains a fixed known relationship between the speed of the transmitting and receiving means and a fixed relationship between the angular positions of the driving and driven shafts. The well-known Selsyn generator and motor system may be employed as driving means 128a, the generator being connected

to the shaft of motor M and the motor being connected to the adjusting screw for the control point 98' through a gear box, if necessary. Thus, there is a fixed relationship, depending upon the constants of driving means 128a, such as the gear reduction ratio and the pitch of the screw driving control point 98', between the amount that control point 98' is moved, and the amount which disc 133 rotates, as we have seen, depends upon the amount of change of the humidity of the unheated, indrawn blast air from a chosen base or standard value.

It has been found through experience that the ideal standard for the wet thermocouple setting is 5 grains of moisture per cubic foot of indrawn, unheated blast air at 85° F. It has also been found that a rise or fall in temperature of the heated air blast entering the furnace of approximately 31° F. for each additional grain of moisture per cubic foot over or under such standard, respectively, will compensate for the increased or decreased chilling effect, respectively, of the added moisture in the unheated, indrawn blast air, and thus cause the heated blast to produce a constant heating effect upon the furnace burden. Therefore, the networks N and N' and the various elements thereof are adjusted so that 5 grains of moisture per cubic foot at 85° F. is the standard, and the drive between disc 133 and control point 98' is made such that control point 98' is moved so that the temperature it demands is raised or lowered 31° F. for each increment of movement of disc 133 corresponding to a rise or fall, respectively, of one grain of moisture per cubic foot, of unheated, indrawn blast air.

Since the various instruments employed, such as the means for determining the humidity of the unheated, indrawn blast air and the means for determining the temperature of the heated blast air entering the furnace are provided with means continuously indicating and recording the phenomena which they detect and control, the operating may continuously observe how the control device is working, and any changes or adjustments of the apparatus to be made, such as are infrequently necessary, are readily apparent.

Although a particular embodiment of the invention has been shown and described for the purposes of illustration, it is obvious that numerous variations may be made by those skilled in the art within the scope of the invention. We therefore claim as novel the following.

We claim:

1. In apparatus for supplying hot blast air to a metallurgical blast furnace comprising a blast air intake pipe, means for heating a portion of the indrawn blast air, a hot blast supply pipe into which the heated air is discharged, means for mixing unheated air with the heated air to control the temperature of the blast, and a mixer valve for controlling the amount of cold air so mixed, the improvement which comprises an automatic control for the temperature of the blast, said control comprising means for measuring the temperature of the hot air blast mixture, means responsive to the last named means to adjust the mixer valve to maintain the temperature of such mixture at a predetermined set point, said means including an adjustable element the setting of which determines the temperature of the blast, means for continuously determining the moisture content per unit volume of the unheated air before being so mixed, said means comprising means for continuously isolat-

ing a sample portion of the unheated blast air, means for bringing such isolated portion to a reduced pressure and to a substantially constant temperature, a wet thermocouple, and means for causing the thus conditioned sample of the unheated blast air to impinge upon the wet thermocouple, and means automatically and continuously responsive to the wet thermocouple for raising and lowering the predetermined set point of the temperature control means as the moisture content of the unheated air before being so mixed rises and falls, respectively, said last named means comprising a balanceable electric circuit, a first variable impedance in such circuit having an element movable as its impedance changes, a control circuit connected to the wet thermocouple, said control circuit including a self-balancing potentiometer in which the voltage of the wet thermocouple is balanced against the effective voltage of the potentiometer resistance, the potentiometer having an element movable as its effective voltage changes, means connecting the movable element of the potentiometer to the movable element of the first variable impedance to cause them to move in synchronism, a second variable impedance in a balanceable circuit, said second variable impedance having an element movable upon change of its impedance, the second variable impedance being similar to the first variable impedance and being symmetrically located in a balanceable circuit with respect thereto, means connecting the movable element of the second variable impedance to the temperature determining adjustable element of the temperature control means, means connected to the movable element of the second variable impedance to move it and the adjustable element of the temperature control means, and control means responsive to the movement of the movable element of the first variable impedance to cause the movement of the movable element of the second variable impedance in an amount corresponding to the movement of the movable element of the first variable impedance.

2. Apparatus for controlling the temperature of the hot blast for a metallurgical furnace which comprises means for heating the blast air, recording means for measuring the temperature of the hot blast air and means responsive to the temperature measuring means to maintain the temperature of the hot air blast at a predetermined set point, said temperature controlling means including an adjustable element the setting of which determines the temperature of the blast, means indicating the setting of the adjustable element, recording means for continuously determining the moisture content per unit volume of the unheated blast air, said last named means comprising means for continuously isolating a sample portion of the unheated blast air, means for bringing such isolated portion of the unheated blast air to a reduced pressure and to a substantially constant temperature, a wet thermocouple, and means for causing the thus conditioned sample of unheated blast air to impinge upon the wet thermocouple, means automatically and continuously responsive to the wet thermocouple for automatically continuously adjusting the adjustable element on the temperature controlling means to effect raising and lowering of the predetermined set point of the temperature control means as the moisture content of the unheated blast air rises and falls, respectively,

said last named means comprising a balanceable electrical circuit, a first variable impedance in such circuit, having an element movable as its impedance changes, a control circuit connected to the wet thermocouple, said control circuit including a self-balancing potentiometer in which the voltage of the wet thermocouple is balanced against the effective voltage of the potentiometer resistance, the potentiometer having an element movable as its effective voltage changes, means connecting said movable element of the potentiometer to the movable element of the first variable impedance to cause then to move in synchronism, a second variable impedance in the balanceable circuit, said impedance having an element movable upon change of impedance and being similar to the first impedance and being symmetrically located in the balanceable circuit with respect thereto, means connecting the movable element of the second variable impedance to the set point of the temperature control means, power means connected to the movable element of the second variable impedance to move it and the set point of the temperature control means, and control means responsive to movement of the movable element of the first variable impedance to cause the movement of the movable element

16
of the second variable impedance in an amount corresponding to the movement of the movable element of the first variable impedance.
